UNITED STATES PATENT OFFICE.

STEWART J. CORT, OF BETHLEHEM, PENNSYLVANIA, ASSIGNOR TO BETHLEHEM STEEL COMPANY, OF BETHLEHEM, PENNSYLVANIA, A CORPORATION OF PENNSYLVANIA.

REGENERATIVE OPEN-HEARTH FURNACE.

Application filed December 21, 1923. Serial No. 681,940.

My invention relates to regenerative open hearth furnaces, more particularly to that type having lateral reentrant or so-called "monkey" walls at the ends of a furnace, and 5 it has for its object to provide a furnace of this character having a roof whose edges terminate at the walls of the furnace including the reentrant portions thereof, whereby air may freely circulate against the exterior walls 10 of the furnace without the formation of dead air spaces or pockets.

A further object of my invention is to provide a regenerative furnace having reentrant side walls at its ends and channel members 15 which follow the outline of and are arranged on top of the walls, the channel members serving to support the roof.

Lateral reentrant or monkey walls for regenerative furnaces serve to impart proper 20 directive effects to incoming combustion gases. The construction of these walls as triangular solid masses of masonry is objectionable on account of the intense heat developed at the region thereof. Consequently, adopting the principle familiar to those skilled in the art that a thin wall provides for a better radiation than a thick wall, it was obvious and logical to avoid thick 25 masonry construction at these points and to provide the monkey wall construction merely by having the side walls indented or made reentrant at the ends, whereby such walls might be of a uniform thickness throughout. In so far as I am aware, however, it has been 30 the customary practice to provide furnace roofs of uniform widths from end to end, so that projecting eaves extend over the reentrant side walls. A roof constructed in this manner limits circulation of air against 35 the exterior of the reentrant walls and forms in effect dead air spaces or pockets with respect to the latter. Appreciating that the durability of these highly heated reentrant walls might be extended by better cooling, I 40 provide a roof construction which is made to follow the outline of the furnace walls.

Apparatus made in accordance with my invention is illustrated in the accompanying drawings, forming a part of this application, 45 in which

Figure 1 is a fragmentary vertical section taken along the line I—I of Figure 2, showing one end of a furnace having my improved monkey wall and roof construction;

55 Figure 2 is a fragmentary plan view of

the portion of the furnace shown in Figure 1;

Figure 3 is a horizontal sectional view taken along the line III—III of Figure 1;

Figure 4 is a vertical sectional view taken 60 along the line IV—IV of Figure 2 looking in the direction of the arrows;

Figure 5 is a perspective and diagrammatic view to show the outline of the monkey walls and the roof; and,

Figures 6 and 7 are detail views showing 65 an arrangement of skew back channels for the reentrant side walls.

In the drawings, I show an open hearth regenerative furnace of the reversing type including a melting chamber 10 which communicates at its ends through ports 11 with end chambers 12, the latter in turn being in communication with air and gas uptakes 13 and 14, respectively.

The melting chamber 10 is defined by substantially parallel side walls 15 which are continuous with inwardly converging wall portions 16 at the ends thereof, the latter walls merging into substantially parallel 80 relatively short walls 17, which are joined to diverging wall portions 18, the latter wall portions constituting the side walls of the end chambers 12. The walls 18 merge into substantially parallel wall portions 19 which 85 constitute outside walls of the air uptakes 13 at the upper ends of the latter. Wall portions 16 and 18 constitute monkey walls of the reentrant type.

In order to give the proper directive effect 90 to gases entering the melting chamber the roofs 20 of the end chambers 12 are inclined downwardly toward the melting chamber as indicated in Figure 1. The inclined roofs 20 are joined by a horizontally extending roof 95 20' for the melting chamber. Since the roofs are crowned and have their lateral edges terminating at the outside edges of the walls 15, 16, 17, 18 and 19, it will be apparent that such crowning necessitates inclination of the tops 100 of the walls 16 downwardly toward the tops of the walls 15. As will be clear from Figure 5 and as may be seen from Figure 1 the tops of the walls 19, 17 and 14 are substantially horizontal but that the walls 19 are 105 higher than the walls 17 and that the latter walls are higher than the walls 15, thereby necessitating downward inclination of the tops of the walls 18 toward the tops of the walls 17 and further downward inclination of 110

the tops of the walls 16 toward the tops of the walls 15.

5 Skew back channels 22 are arranged at the tops of the walls 15, 16, 17, 18 and 19 and such channels follow the outline of the side walls. The roofs 20 and 20' are supported in the usual manner by the skew back channels.

10 Buckstays 24 cooperate with the outside of the skew back channels and tension rods 25 connect opposed buckstays in the ordinary way. Upon reference to Figures 2, 3, 6, and 7, it will be noted that one pair of buckstays 24' is inset in order to afford lateral support to the inset or knuckle portion 26 of the skew 15 back channel 22 which rests on top of the wall portion 17, opposed buckstays 24' being secured together by the tension rod 25'. The downwardly-inclined portions 27 and 28 of the skew back channels arranged, respectively, above the wall portions 18 and 16 receive considerable thrust due to the load of the roof; and, consequently, I further brace the portions 27 and 28 of the skew back channel by means of braces 29 and 30 connected to 20 buckstays 24' below the skew back channel and connected to the portions 27 and 28 of the latter at intermediate points between the buckstays 24' and the adjoining buckstays 24.

30 In addition to the tension rods for holding the buckstays in position the latter are supported in a well-known manner by binding members 31.

35 From the foregoing description, it will be apparent that I have provided a regenerative furnace having reentrant monkey walls at its ends with a roof construction which terminates at the outside or upper edges of the walls, thereby avoiding any outwardly-ex-

tending eaves and providing for free circulation of air against the walls and avoiding 40 the formation of dead spaces or pockets, whereby the reentrant monkey walls are cooled to the best advantage.

45 While I have shown my invention in but one form, it will be obvious to those skilled in the art that it is not so limited, but is susceptible of various other changes and modifications without departing from the spirit thereof, and I desire, therefore, that only 50 such limitations shall be placed thereupon as are imposed by the prior art or as are specifically set forth in the appended claim.

Having thus described the invention what is claimed as new and desired to be secured by Letters Patent is:

55 In an open hearth furnace, the combination of substantially parallel side walls, converging side walls at the ends of the substantially parallel walls, relatively short substantially parallel walls at the ends of the converging walls, diverging walls beyond the last named substantially parallel walls, substantially parallel walls beyond the diverging walls, skew back channels following the outline of and arranged at the top of said walls, buckstays 60 resting against the parallel portions of said walls, and bracing means between the buckstays for the parallel walls between the converging and diverging walls and the converging and diverging skew back channels 65 at the top of the converging and diverging walls, and a roof supported by the skew back channels.

70 In testimony whereof I hereunto affix my signature this 5th day of December, 1923.

STEWART J. CORT.
